ELECTRIC SWITCH MECHANISM

Charles J. Hull, North Tonawanda, N. Y., assignor to The Rudolph Wurlitzer Company, North Tonawanda, N. Y., a corporation of Ohio

Application October 18, 1939, Serial No. 300,041

7 Claims. (Cl. 260—33)

This invention relates to electrical switches but more particularly to a switch whose contacts are held in conducting relation for a predetermined time and then broken without effort or care on the part of the operator.

An object of the invention is to provide a switch mechanism which requires but a single push of a button to make or break switch contacts, yet holds such contacts closed or open for a definite or predetermined period of time and then automatically opens or closes them depending upon the nature of the circuit of the switch mechanism control.

Another object of the invention is to provide a switch mechanism which is adaptable to various uses, which is simple and rugged in construction and reliable and efficient in operation and which is composed of a minimum number of parts.

Other features of the invention reside in the construction and arrangement of parts hereinafter described and particularly pointed out in the appended claims.

In the accompanying drawing:

Figure 1 is a side elevational view of the switch mechanism embodying my invention. Figure 2 is a similar view looking at the opposite side thereof. Figure 3 is an enlarged longitudinal section taken on line 3—3, Figure 7, showing the parts in their normal or inoperative position. Figure 4 is a similar view showing the parts in an operative or time-governed switch closing position. Figure 5 is a similar view showing the parts in a position immediately after the switch has been automatically opened or at the end of its operative, time-governed position. Figures 6 and 7 are vertical sections taken in the plane of the correspondingly numbered lines in Figure 1.

Similar characters of reference indicate corresponding parts throughout the several views.

It is desirable, in certain circuit set-ups, to cause the circuit to be closed at a switching point for a sufficient time to effect a certain result, as for example, to cause current to flow through the coil of an electro-magnet for a predetermined time to insure saturation of its core and overcome the inertia of its armature to effect the proper performance of the secondary function of the magnet. When such a switch is left completely to the control of the user, particularly by an unskilled person, the time element may not be sufficient to properly perform the functions required of a particular circuit. To obviate this condition and eliminate guess work on the part of the user, I have created a switch mechanism which requires but a push button action on the

part of the operator, while the time element or period of closure of the circuit is automatically controlled.

By way of example, my invention has been shown in connection with a switch unit including a supporting block or body 10 having mounted on its top side spaced, parallel switch elements 11, 12 and an intervening movable switch element 13, which normally engages the companion lower switch element 11, as shown in Figures 1, 2 and 3 to maintain a given circuit closed, and which is adapted to be projected into contact with the upper switch element 12, as shown in Figure 4, to maintain the circuit thereof closed for a predetermined period of time. At its free end the movable switch element has an insulated actuating head 14. At its lower side the body 10 has an enlarged boss or guide hub 15 in which a manually-operated push rod or plunger 16 is slidably mounted for initiating the movement of the switch element 13 upwardly into contact with the companion switch element 12. A coil spring 17 applied to the push rod tends normally to urge it to its retracted or inoperative position shown in Figure 3, and in which position a stop pin 18 borne by the rod abuts against the adjoining edge of the body 10 to limit its retracted movement.

Actuated in response to the forward or operative stroke of the push rod 16, for actuation in a combined longitudinal and vertical direction into a position to bring the movable switch element 13 into contacting engagement with the companion element 12 and for subsequently maintaining such switch elements closed for a predetermined time, is a substantially L-shaped striker plate or switch-governing lever 19 having a fulcruming stud or pin 20 at its outer end engaging a longitudinal guide-way or groove 21 formed in the face of the body 10 and relative to which such lever is adapted for longitudinal movement as well as a vertically-swinging movement about its fulcruming axis. The inner or free offset end of this switch-governing lever has a laterally-bent lug 22 thereon which is normally disposed in the path of endwise travel of the push rod 16 for actuating such lever in the manner stated. At its top edge the lever 19 has a switch-engaging surface or dwell 23 which is adapted to contact the switch-head 14 and elevate it to close the switch-elements 12, 13 and maintain them closed, the length of such dwell surface being predetermined in accordance with the time element desired for a given switch-closing condition or operation. For the purpose of

guiding the lever into its switch-closing and sustaining positions and subsequently effecting its return to initial position wherein the switch elements 11 and 13 are again closed, said lever has a follower pin or roller 24 extending from its inner face and adjacent the free end thereof which engages an endless cam-groove 25 formed in the opposing face of the body 10 and of substantially rectangular shape in plan, as clearly shown in Figure 3. A spring 26 connected at one end to the lever 19 and at its other end to the body 10 serves to normally urge the lever to its normally retracted and downwardly-swung position shown in Figures 2 and 3, in which position the follower pin is lodged at the lower near corner of the cam-groove, while the fulcruming stud 20 is in abutting contact with the rear end of its companion guide-way 21 with the lever-lug 22 adjoining the end of the push rod 16.

A cover plate 27 is preferably applied to the grooved face of the body 10 and over the switch-governing lever 19 and is notched at 28 to allow for the free movement of the lever-spring 26.

In operation, assuming the parts to be in the normal inoperative position shown in Figure 3, with the switch elements 11 and 13 closed, and it is desired to break such connection and close the companion switch elements 12 and 13 for a predetermined period of time, the operator presses the push rod 16 forwardly its maximum stroke and releases it immediately, whereupon the spring 17 promptly returns it to its initial position. During its forward stroke, the push rod encounters the lug 22 of the switch-governing lever 19 and projects the latter forwardly in a horizontal plane against the resistance of the spring 26 until the follower pin 24 encounters the inclined portion of the groove 25, at which time said lever is swung upwardly about its traversing pivot-stud 20, to bring its surfaces 23 into contact with the actuating head 14 of the movable switch element 13 to elevate the same into engagement with the companion element 12 and out of engagement with the normally-closed element 11, as shown clearly in Figure 4, in which position the push rod is in its extreme advanced position. Upon the release of the push rod, it is promptly returned by its spring 17 to its normal position, while the switch-governing lever is restored independently to its position by the spring 26. During the restoring stroke of such lever, it is initially guided in a horizontal plane in the upper portion of the groove 25 to thereby retain the switch 12, 13 closed for a period of time determined by the length of the lever-surface 23, after which the lever is urged downwardly by the spring 26 with its follower pin 24 engaging the upright portion of said groove and with the result that the switch-head 14 rides off the lever to automatically open the switch elements 12, 13 and again close the switch elements 11, 13.

It will be seen that no matter how rapidly or slowly the push rod 16 is depressed by the operator, it does not in any way alter the length of time the switch contacts are held closed and opened. If the operator holds the push rod in for an abnormal period at the end of its forward stroke, the rod-engaging lug 22 on the switch-governing lever 19 rides off the end of the push rod, as shown in Figure 4, and engages the top side of such rod until the latter is released.

I claim as my invention:

1. In a switch mechanism of the character described, a support having guide means there-

on, a pair of companion switch elements mounted on said support, one of which is movable relatively to the other to and from a switch-closing position, a member slidably engageable with said guide means and projectable to and from operative engagement with said movable switch element for sustained engagement therewith during its cycle of movement to maintain the switch elements closed over a predetermined time period, and means engageable with said member for initiating its movement to a projected switch-closing position.

2. In a switch mechanism of the character described, a pair of companion switch elements, one of which is movable relatively to the other to and from a switch-closing position, a member movable longitudinally relatively to said switch elements and projectable to and from operative engagement with said movable switch element for governing its closing and opening movements, means connected to said member for normally urging it to a switch-opening position, and means engageable with said switch-governing member for guiding it longitudinally in sustained engagement with the movable switch element for a predetermined time during the movement of such member to switch-opening position.

3. In a switch mechanism of the character described, a pair of companion switch elements, one of which is movable relatively to the other to and from a switch-closing position, a member movable longitudinally relatively to said switch elements and projectable to and from operative engagement with said movable switch element for governing its closing and opening movements, means connected to said member for normally urging it to a switch-opening position, means engageable with said switch-governing member for guiding it longitudinally in sustained engagement with the movable switch element for a predetermined time during the movement of such member to switch-opening position, and a normally-retracted push rod for projecting said switch-governing member toward switch-closing position.

4. In a switch mechanism of the character described, a pair of companion switch elements, one of which is movable relatively to the other to and from a switch-closing position, a combined vertically-swinging and horizontally displaceable member operatively engageable with said movable switch element for governing its opening and closing movements, a spring connected to said member for normally urging it vertically and horizontally to a switch-opening position, and means engageable with said switch-governing member for guiding it in its vertical and horizontal paths of displacement.

5. In a switch mechanism of the character described, a pair of companion switch elements, one of which is movable relatively to the other to and from a switch-closing position, a combined vertically-swinging and horizontally displaceable member operatively engageable with said movable switch elements for governing its opening and closing movements, a spring connected to said member for normally urging it vertically and horizontally to a switch-opening position, and means engageable with said switch-governing member for guiding it in its vertical and horizontal paths of displacement, said guide means including a portion for maintaining said member in sustained engagement with the movable switch element during the horizontal dis-

placement of such member in a direction to open the switch.

6. In a switch mechanism of the character described, a pair of companion switch elements, one of which is movable relatively to the other to and from a switch-closing position, a combined vertically-swinging and horizontally displaceable member operatively engageable with said movable switch element for governing its opening and closing movements, said member having a horizontally-extended contact face for engagement with the movable switch element for predetermining the duration of closing of the switch, a spring connected to said member for normally urging it vertically and horizontally to a switch-opening position, and means engageable with said switch-governing member for guiding it in its vertical and horizontal paths of displacement.

7. In a switch mechanism, a body having a

pair of companion switch elements thereon, one of said elements being movable relatively to the other to and from a switch-closing position, said body having a longitudinal groove and an endless groove therein, a vertically-swinging and horizontally-displaceable switch-governing lever mounted on the body and having a pivot guided in said longitudinal groove and a follower pin engaging said endless groove, the upper surface of said lever being adapted for engagement with said movable switch element and being of a length to predetermine the duration of closing of the switch, a spring applied to said lever for normally urging it to a retracted switch-opening position, and a push rod engageable with said lever for actuating it to its initial switch-closing position.

CHARLES J. HULL.
